UNITED STATES PATENT OFFICE.

SAMUEL SEABURY, OF STONY BROOK, NEW YORK.

APPARATUS FOR HANDLING AMMUNITION.

SPECIFICATION forming part of Letters Patent No. 366,348, dated July 12, 1887.

Application filed March 19, 1887. Serial No. 231,496. (No model.)

To all whom it may concern:

Be it known that I, SAMUEL SEABURY, of Stony Brook, in the county of Suffolk and State of New York, lieutenant United States Navy, have invented a new and useful Improvement in Devices for Handling Ammunition, of which the following is a specification.

The object of my invention is to provide a convenient device which may be lowered over a projectile or other ammunition when the latter is standing in an upright position, and which, by the swinging of a bail provided upon it into a position for hoisting the shell or ammunition, will be made to engage automatically with the shell or ammunition for lifting it; also, to so construct the device that it will serve to protect the breech of the gun in passing the shell or ammunition from it into the gun.

In its most complete form my improved device includes a cylindric casing which is open at both ends and substantially closed as to its side wall or periphery, and which has expanding members adapted to engage the ammunition by contraction thereon, and clamping devices whereby the expansible members may be contracted on the ammunition to engage with it for lifting it. The case may be longitudinally divided, and may have connected with it pivotally a bail for lifting it, which serves, when swung upward into lifting position in line with the axis of the case, to contract the members of the case into lifting engagement with the ammunition. The bail may be provided with handles which when extended horizontally from opposite sides serve as a means of carrying the case with its contained ammunition. The bail engages with trunnions on the case, and the case is preferably divided longitudinally through these trunnions, and the bail is provided with cams whereby the sections of the case are moved apart to expand the case and release the ammunition when the case is swung into approximately horizontal position for loading. I also provide in connection with the case a stop for preventing forward movement of the ammunition in the case and a sliding bolt on the case which, when moved rearward by contact with the gun, serves to retract the stop from the path of the ammunition. The bail has

eyes which are elongated in the direction of its length, and which receive the trunnions, and consequently when the bail is swung into position lengthwise of the case, as in lifting, 55 its elongated eyes serve as clamping devices for contracting the case into lifting engagement with the ammunition.

The invention consists in novel combination of parts and features of construction, which 60 are hereinabove referred to and hereinafter described, and pointed out in the claims.

In the accompanying drawings, Figure 1 represents my improved device as slipped over a projectile preparatory to lifting the 65 same. Fig. 2 represents the device having its bail swung upward into line with the case, so as to contract the case into engagement with the projectile for lifting the latter. Fig. 3 is an elevation similar to Figs. 1 and 2, but in a 70 plane at right angles thereto, representing the handles whereby the case and contained ammunition may be lifted and carried by hand as in operative position. Fig. 4 is a longitudinal section of the breech portion of a gun, 75 showing my improved device as in loading position relatively to the gun to enable the projectile to be slipped lengthwise from the handling device into the gun. Fig. 5 is a longitudinal section through the case, representing 80 the lower half thereof in plan view. Figs. 6 and 7 are end views of the case and projectile, including a sectional view through the trunnions and the bail-eyes, Fig. 6 representing the bail as swung into a position for contracting 85 the divided case upon a projectile, and Fig. 7 representing the bail as swung into a position to permit of the ammunition being slipped from the case into the gun; and Fig. 8 is a face view, upon a larger scale, representing 90 a portion of the divided case and one of the bail-eyes which is applied to the trunnions of the case, showing the eye in such position relatively to the case as to constitute a clamping device for contracting the two sections or 95 members of the case into lifting engagement with the projectile.

Similar letters of reference designate corresponding parts in all the figures.

A designates the projectile or ammunition, 100 which may be either a cartridge, a solid shot, or a shell, and the device which I shall now de-

- scribe is intended to be slipped downward over the ammunition when it is supported on its end near the shell room or magazine, to contract into lifting engagement with the ammunition by the very act of drawing upward upon the tackle B, whereby the ammunition is to be lifted and to support the ammunition in horizontal position preparatory to and during its insertion in a gun.
- 10 The device consists in its essential elements of a cylindric case which comprises expanding members, and in this example of my invention the cylindric case is composed of two sections or members, C C', or, in other words, is longitudinally divided, and its sections or members are formed with an internal shoulder, c, adapted to engage a corresponding shoulder, c', upon the projectile A. When the cylindric case C C' is expanded, as shown in Fig. 1, it may be slipped freely downward, as shown in Fig. 1, upon the ammunition, so as to bring the shoulder c below the shoulder or projection c'; but after contraction of the cylindric casing the shoulder c is brought into lifting engagement with the shoulder c', as represented in Fig. 2, and by means of the casing C C' the ammunition may be lifted.
- 15 In this example of my invention the case is provided with a bail, D, pivotally connected with its opposite sides, and through which the case and its contained ammunition are lifted, and this bail is so constructed that when swung upward into position lengthwise of the case, as shown in Figs. 2 and 3, its eyes, which receive the trunnions c² of the case, constitute clamping devices for contracting the two sections C C' of the case into lifting engagement with the ammunition. The bail is also so constructed that when the ammunition-case C C' is swung into horizontal position and suspended by the bail D, as represented in Fig. 4, preparatory to transferring the ammunition A from the case to the breech of a gun, E, the sections C C' of the case will be separated and the ammunition A, by a rammer, E', may be slipped forward from the case C C' into the breech of the gun E. The longitudinal line of division c³ of the case is through the trunnions c², and the eyes d of the bail which receive the trunnions c² are elongated in the direction of the length of the bail, and when the bail is swung upward into the positions shown in Figs. 2, 3, and 8 the divided trunnion c² rests in the lower portion of the elongated eye d, and the two eyes d at opposite ends of the bail, by their action upon the divided trunnions, constitute clamping devices for contracting the cylindric case C C' into lifting engagement with the ammunition A.
- 20 In order to expand the case-sections C C' when the case with its contained ammunition is swung into the position shown in Fig. 4, I provide cams upon the bail D. As here represented, a cap-plate, F, is applied to each divided trunnion, said plate being secured by screws f rigidly to one trunnion-section, and being connected by a screw and slot, f' f², with

the other section. In the covering-plate F is an inwardly-projecting pin, f³, which engages a slot, f⁴, in the bail D, and at one end portion 70

this slot is inclined, as shown at f⁵, so that by acting upon the pin f³ it will lift the section C of the case, which is uppermost when the case is swung into a horizontal position. The cover-plate F also has a stop-pin, f⁶, and the 75 bail D has shoulders f⁷ f⁸, which, by coming against this stop-pin, limit this swinging movement of the bail D relatively to the case C C'.

To enable the case C C' and its contained ammunition to be carried by hand, I provide 80 handles D', which are represented as pivotally connected at d' with the bail D, so that they may be swung into horizontal position, as shown in Fig. 3, when desired for use, and will drop downward into the position shown by 85 dotted lines in Fig. 3 when not desired for use.

In order to prevent the ammunition A from sliding forward prematurely into the breech of the gun E by reason of the rolling of the vessel, or from any other cause, before the case has been inserted to its full extent into the breech of the gun E, I have represented a stop-pin, h, as projecting through an oblique slot, h', into the lower section, C', of the case, 90 and this stop-pin h is connected with or projects from a longitudinally-sliding bolt, h², which normally projects slightly forward of the case-section C', as is shown in Fig. 5, and has applied to it a spring, h³, for so projecting it forward. The bolt h² slides in a frame, h, which is secured upon the lower section, C', of the case, and which, when the case is inserted into the breech of the gun, enters the groove or channel cut through the screw-thread of the 100 breech, and which receive one of the threaded projections on the breech-block when the latter is slipped into the breech preparatory to turning it into engagement with the thread. The section C' of the case has a forward projection or lip, c⁴, which is of such length as to 110 prevent contact of the ammunition A therewith in inserting the ammunition into the gun E. It is obvious that any sliding movement 115 imparted to the bolt h² will, by reason of the oblique or cam-like slot h' acting upon the pin h, cause the bolt h² to turn on its axis, and thereby retract the stop-pin h from the path 120 of the ammunition, so as to permit of the ammunition being readily slipped forward into the gun. When the case C C' is inserted into the breech of the gun, as shown in Fig. 4, this bolt h² at its forward end strikes the gun and is pushed back relatively to the case C C', thereby retracting the stop h from the path of the ammunition and permitting the ammunition to be slipped forward into proper position in the gun.

What I claim as my invention, and desire 130 to secure by Letters Patent, is—

1. The device herein described for handling ammunition, consisting of a cylindrical case which is substantially closed as to its side

- wall or periphery and open at the ends, and which has projecting from its inner surface near the lower end expanding members adapted to engage the ammunition by contraction thereon, and a bail pivotally connected with the case and serving when swung into position for lifting to contract the members into lifting engagement with the ammunition, substantially as herein described.
- 5 2. The combination, with a longitudinally divided and expansible case open at both ends, and having trunnions formed in part upon each section of the case, of a bail having eyes which receive the divided trunnions and which serves when swung upward into lifting position to contract the members of the case into lifting engagement with the ammunition, substantially as herein described.
- 10 3. The combination, with a longitudinally divided and expansible case for receiving ammunition, of a bail pivotally connected with the case and serving both to lift it and by swinging to contract its members into lifting engagement with the ammunition, and handles secured to the bail to project laterally therefrom, whereby the case and contained ammunition may be carried, substantially as herein described.
- 15 4. The combination, with a cylindrical and expansible ammunition - case having trunnions and divided through its trunnions, of a bail swinging on the trunnions and having cams whereby the members of the case are moved apart to expand the case and release

the ammunition when the case is swung into 35 approximately horizontal position for loading, substantially as herein described.

5. The combination, with a cylindrical case for containing ammunition and for lifting it to the breech of a gun, of a stop for preventing forward movement of the ammunition in the case, and a sliding bolt on the case, which when moved by contact with the gun serves to retract the stop from the path of the ammunition, substantially as herein described. 45

6. The device herein described for handling ammunition and loading guns therewith, consisting of a cylindrical case having expanding members, and having a forward projection or lip for entering the breech of the gun, and 50 clamping devices whereby the members may be contracted into lifting engagement with the ammunition, substantially as herein set forth.

7. The combination, with the case C'C', having trunnions and divided longitudinally 55 through the trunnions, of the bail D, having eyes for receiving the trunnions, and which are elongated in the direction of its length, so that when the bail is swung into position lengthwise of the case, as in lifting, its eyes serve as 60 clamping devices for contracting the case into lifting engagement with the ammunition, substantially as herein described.

SAMUEL SEABURY.
